UNITED STATES PATENT OFFICE.

HENRY BARDSLEY, OF PROVIDENCE, RHODE ISLAND, ASSIGNOR TO CROMPTON & KNOWLES LOOM WORKS, OF PROVIDENCE, RHODE ISLAND, A CORPORATION OF RHODE ISLAND.

SHUTTLE-BOX-OPERATING MECHANISM FOR LOOMS.

SPECIFICATION forming part of Letters Patent No. 693,681, dated February 18, 1902.

Application filed November 18, 1901. Serial No. 82,618. (No model.)

To all whom it may concern:

Be it known that I, HENRY BARDSLEY, a citizen of the United States, residing at Providence, in the county of Providence, State of Rhode Island, have invented a certain new and useful Improvement in Shuttle-Box-Operating Mechanisms for Looms, of which the following is a specification, reference being had therein to the accompanying drawings.

10 The invention has relation to shuttle-box-operating mechanism of that class in which an intermittently-operated master-gear partially rotated step by step is employed for the purpose of actuating, under the control of pattern devices, the train or trains of operating and transmitting connections through which the box-lever is moved to shift the shuttle-boxes and in which a train such as just has been referred to comprises a partially-toothed or mutilated pinion which at times is engaged and given a semirevolution by the said master-gear, a crank or eccentric rotating in unison with said pinion, and operative connections from said crank or eccentric to the box-lever.

15 The object of the invention is to provide means for causing further actuation of the partially-toothed or mutilated pinion or pinions aforesaid by the master-gear to be prevented when the weft-detector devices act to indicate the occurrence of the predetermined condition of the weft or filling, thereby preventing any further change or shift of the position of the shuttle-boxes during the continued working of the loom mechanism.

20 The invention consists in the novel devices which I will now proceed to explain with reference to the accompanying drawings, in which latter I have shown the best embodiment of the invention which I have thus far contrived.

25 In the accompanying drawings, Figure 1 shows in side elevation portion of one side frame of a loom having the said embodiment of the invention applied thereto. Fig. 2 is a plan view, partly in section, showing the compound box-lever. Fig. 3 is a detail view illustrating a convenient and well-known arrangement of weft-detector devices and the man-

30 ner of operating therefrom the disengaging device, to which reference is made hereinafter. Fig. 4 is a detail view in elevation showing the master-gear, one of the partially-toothed or mutilated pinions, and the disengaging device. Fig. 5 shows the parts of Fig. 4 in side elevation.

Having reference to the drawings, 1 designates portion of one of the side frames of a loom.

5 5 is the master-gear. It is in practice 60 moved intermittently the distance of a partial revolution, as usual. Any suitable or known operating means therefor may be provided—as, for example, means similar to that of my United States Letters Patent No. 65 681,648, granted August 27, 1901. 54 is the sleeve of the master-gear, and 4 is the segmental gear on said sleeve, as in the said patent.

51 51, &c., are the toothed segments with 70 which the master-gear 5 is provided for the actuation of the partially-toothed or mutilated pinions.

One of the partially-toothed or mutilated pinions is shown at 6, Figs. 1, 4, and 5, the 75 places of two more of such pinions being indicated by dotted circles in Figs. 1 and 4. Each of the said pinions has connected therewith a crank, as 61, or other motion-transmitting device, the said crank in the present instance being connected by means of a link or connecting-rod, as 62, with the box-lever. The number of pinions employed and the character and arrangement of the box-lever will vary according to the number of cells 80 that is contained in the series of shuttle-boxes. The said cells vary in number in different cases in practice as required. The illustrated mechanism has been designed for operating a series of shuttle-boxes containing six cells. 85 Accordingly there are three pinions, and the box-lever 7 is a compound lever. What for the purposes of this case may be termed the "main lever" 71 of the box-lever is connected pivotally with the forward extremity of 90 the secondary lever 72. The main lever 71 has pivotally connected with its forward extremity the link 8, extending upward and con-

95

nected pivotally with the box-rod 81 and has connected with its rear extremity one of the connecting-rods 62. The secondary lever 72 has connected therewith two of the said connecting-rods, one at the rear extremity thereof and one at an intermediate point. The action of the cranks in operating the compound box-lever and shifting the shuttle-boxes is well understood by those who are skilled in the art. At 9 is shown a radius-arm, which has one extremity pivotally connected with the rear extremity of the main lever 71, while the other extremity of said radius-arm is pivoted, as at 91, to the side frame 1 of the loom, this radius-arm serving to steady the compound box-lever in its movements.

Each mutilated pinion 6 in the illustrated embodiment of the invention is furnished with a diametrical lever 10 on the order of that which is shown and described in my prior United States Letters Patent, No. 626,960, granted June 13, 1899, the respective diametrical levers being controlled, as in the said patent, by a pattern-surface and intervening operative connections, the said connections comprising in part the levers or fingers 11 111 112 and rock-shafts 12 121.

At 52 52, &c., are the starting-teeth with which the master-gear 5 is provided. The said starting-teeth are designed to engage in the rotation of the master-gear with the inwardly-directed extremities of the diametrical levers when the said levers are swung by the pattern connections into position to place the said inwardly-directed extremities thereof within the range of movement of the starting-teeth 52 52. This engagement operates to partially rotate the predetermined pinion or pinions far enough to bring teeth of the latter around for engagement with the segments 51 51 of the master-gear, whereby the said segments of the master-gear are enabled to occasion a semirevolution of the said predetermined pinion or pinions.

At 53 53, &c., are shown the plain concentric surfaces or rests with which the master-gear is provided intermediate the segments 51 51, &c., for coaction with the toothless portions 61 61 of the pinions 6 in holding the pinions from rotating between the predetermined times of movement therefor.

No novelty is claimed for the foregoing features, all of which are or may be essentially as heretofore.

As will be apparent the extremities of the diametrical levers constitute movable starting-teeth for the mutilated pinions, the said extremities being brought within the range of action of the starting-teeth of the master-gear by the pattern mechanism when it is desired that a pinion shall be given a semi-revolution.

For the purpose of preventing further actuation of the mutilated pinion or pinions by the master-gear after the weft-detector devices have acted to indicate the occurrence

of the predetermined condition of the weft or filling I provide means in operative connection with the weft-detector devices and by which on such occurrence working relations between the mutilated pinion or pinions and the master-gear are disestablished through the action of said weft-detector devices. The desired result may be effectuated in various ways within the spirit of my invention. The said invention is not restricted to the particular embodiment that is illustrated in the drawings. In constructions having starting-teeth which are shifted by the pattern mechanism into engaging position for the purpose of bringing about a change of the shuttle-boxes the said result is attained by causing such starting-teeth to occupy positions in which engagement cannot occur. In the present embodiment of the invention I provide means for causing the diametrical levers to occupy positions in which their inwardly-directed extremities are out of the range of movement of the starting-teeth with which the master-gear is furnished. Preferably, although not necessarily in all embodiments of the invention, the said means is caused to engage with the said inwardly-directed extremities. In the drawings a rotary disengager *a* is shown, it being mounted concentrically with relation to the master-gear. The said disengager is provided with a series of arms *a' a' a' a'* to act against the inwardly-directed extremities of the diametrical levers and with a sleeve *a²*, Fig. 5, fitted within sleeve 54 of the master-gear. The arms *a' a'*, &c., project radially outward from the center of the master-gear, the extremities thereof entering into the intervals between the toothed segments 51 51, &c., of the master-gear. The said toothed segments have at the opposite ends thereof inwardly-extending enlargements 54 54. The extremities of the arms *a' a'*, &c., fit between pairs of these enlargements, as shown in Fig. 4, and by the engagement of the said enlargements with the disengager the latter in the present embodiment of the invention is caused to rotate in unison with the master-gear. The normal position of the disengager (shown by dotted lines in Fig. 5) leaves the diametrical levers free to be moved by the action of the pattern mechanism in a direction to carry the inwardly-directed extremities of said levers laterally within the intervals between the pairs of starting-teeth 52 52 into position to be engaged by said starting-teeth in the rotation of the master-gear to start the pinions 6. (See the dotted-line position of lever 10 in Fig. 5.) Movement of the disengager laterally outward from its position in Fig. 5 will cause it to hold the levers 10 in a position to clear the starting-teeth 52 52, &c. The said starting-teeth are constituted by the opposite ends of flanges *b b*, &c., projecting laterally from the segments 51 51, &c., of the master-gear. The edges of these flanges while passing the diametrical

levers act to hold the inwardly-directed extremities of the latter clear of the ends of the teeth of the segments 51 51.

The disengager may be operatively combined with any suitable form or arrangement of weft-detector devices. In Fig. 3 I have shown simple weft-fork mechanism, the same comprising, essentially, the gooseneck *c'*, only part of which is shown, the weft-fork *c*, its 5 slide *d*, mounted on top of breast-beam *d'*, and the rod *e*, mounted beneath the breast-beam in bearings, in which it is free to rock, and provided with the arm *e'*, arranged to be 10 acted against by the slide *d*. Rod *e* is provided also with the arm *e²*, which is connected by a wire or rod *f* with arm *g'* on a rock-shaft *g*, extending from front to rear in the loom, the said rock-shaft being furnished at its rear end with a shipper-fork *h*, engaging with the 15 grooved hub *i* on the sleeve *a²* of the disengager. When the weft or filling fails or breaks and the tail of weft-fork *c* is engaged by gooseneck *c'*, so that the slide *d* is pushed 20 forwardly on the breast-beam and rod *e* is turned, rocking the rock-shaft *g*, the shipper-fork *h* on said rock-shaft acts to move the disengager out of its normal inoperative position, 25 (shown in dotted lines in Fig. 5,) so as to hold the diametrical levers out of engagement 30 with the starting-teeth 52 52, &c., of the master-gear.

What I claim is—

1. In combination, the master-gear, the mutilated pinion and its motion-transmitting 35 connections, weft-detector devices and means under operative control of said weft-detector devices whereby operative relations between the master-gear and pinion are disestablished on the occurrence of the predetermined condition of the weft, substantially as described.

2. In combination, the master-gear, the mutilated pinion and its motion-transmitting 40 connections, weft-detector devices, and means under operative control of said weft-detector devices whereby engagement of said mutilated pinion by said master-gear to actuate the former is prevented on the occurrence of the predetermined condition of the weft or filling, substantially as described.

3. In a loom, an organized mechanism comprising, essentially, in combination, a mas-

ter-gear and a mutilated pinion having starting-teeth which are adapted to be shifted into engaging position to occasion the actuation of the said pinion, pattern connections to control such shift, weft-detector devices, and means under operative control of said weft-detector devices whereby said starting-teeth are caused to occupy an inoperative position to thereby prevent the actuation of the pinion, substantially as described. 55

4. In combination, the master-gear, the mutilated pinion, and its diametrical lever, pattern connections in control of said lever, weft-detector devices, and means under operative 65 control of said weft-detector devices whereby engagement of said lever by said master-gear is prevented on the occurrence of the predetermined condition of the weft or filling, substantially as described. 70

5. In combination, the master-gear, the mutilated pinion and its diametrical lever, pattern connections in control of said lever, the disengager coacting with said lever, and weft-detector devices, in operative control of said 75 disengager whereby engagement of said lever by said master-gear is prevented on the occurrence of the predetermined condition of the weft or filling, substantially as described.

6. In combination, the master-gear, the mutilated pinion and its diametrical lever, pattern connections in control of said lever, the disengager at the side of said master-gear, and weft-detector devices having operative 80 connections with said disengager whereby to move the same laterally, substantially as described.

7. In combination, the master-gear, the mutilated pinion and its diametrical lever, pattern connections in control of said lever, the 85 disengager at the side of said master-gear and rotating in unison therewith, and weft-detector devices having operative connections with said disengager whereby to move the same laterally, substantially as described. 90 95

In testimony whereof I affix my signature in presence of two witnesses.

HENRY BARDSLEY.
